COWL

Daniel Friedman, Chicago, Ill.

Application March 8, 1940, Serial No. 323,004

5 Claims. (Cl. 98—70)

This invention relates to a cowl or ventilator for chimneys, stacks and the like, the general object of the invention being to provide a cowl which can be manufactured to sell at low cost and which will work under practically all conditions as it is provided with means at the front for preventing the entrance of gusts of wind which might be directed against the front part of the device when the same is facing a high wall or for any other reason.

Another object of the invention is to provide means whereby the device can be adjusted to suit chimneys or stacks of different diameters and also to provide a passage along the top of the device for the passage of air which will cause a suction in the stack or chimney.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a vertical sectional view of the device showing the same placed on a stack.

Figure 2 is a top plan view of the device.

Figure 3 is a view looking toward the outlet end of the device.

Figure 4 is a bottom plan view of the cowl.

Figure 5 is a view similar to Figure 3 but showing the cowl alone.

Figure 6 is a view of the blank from which the cowl is formed.

Figure 7 is a view of the ring support and its tubular bracket.

Figure 8 is a side view of this ring member.

Figure 9 is a view of the rod supported by the bracket and the ring member and which rotatably supports the cowl.

Figure 10 is a view of the blank for forming the deflector member.

The body part of the cowl is formed of a blank B shown in Figure 6 which has its lower edge of substantially arcuate shape with projections 1 at the junction of the side edges with the lower edge and with the side edges converging and the top of the blank is formed with a substantially crescent-shaped opening 2 and said top being cut away to provide flat ends on the projecting parts 3 formed by the recess or opening 2. This blank is bent to place the ends 1 opposite each other with their terminals overlapping and

connected together as shown at 1' and these ends and adjacent portions of the sides form the bottom of the cowl body which has a large circular opening 4 therein with the sides extending vertically as shown at 5 and joining the curved top 6 which slopes downwardly from the discharge end to the inlet end and with the parts 3 overlapping at the rear and connected together as shown at 7 and these parts forming a rounded end which is spaced from the adjacent end of the rounded top to leave an opening 8 for the inlet of air. A plate 9 has one end bent over the bottom wall of this opening 8 as shown at 10 with the plate extending from one side part of the curved top 6 to another side part so that the plate forms a passage between itself and the rounded part of the top 6 with the upper end of the plate or free end thereof extending upwardly and forwardly as shown at 11 to provide a lip directing the air passing through the passage upwardly before passing from the cowl. A metal bracket 12 has a depending part connected by a fastening means 7 to the inlet end of the cowl with the bracket extending under the plate 9 and having its inner end bent downwardly as shown at 13. A second bracket 14 is connected to the top of this plate 9 and to that part of the bracket 12 which engages the plate by the bolts 15 and this bracket 14 has an upwardly extending portion which extends practically to the top 6 and is then bent first into substantially U-shape as shown at 16 and then into angle shape as shown at 17, the lower limb of the angle part 17 and the lower limb of the U-shaped part 16 having holes therein for receiving a short supporting member and the plate 9 is also provided with a hole for the passage of this supporting member. Furthermore, a transversely extending bracket 18 extends under the plate 9 and has a hole therein for the support member and the ends of the bracket 18 are bent downwardly and connected with the side portions of the cowl by the bolts 19. Thus the parts of the cowl and the plate 9 are firmly connected and braced.

A split ring 20 is adapted to be placed on a chimney or stack S and to be fastened thereto by bolts or rivets 21. This ring is made of bendable material so that it can be adjusted to suit the diameter of the stack or chimney on which it is placed. An upwardly and inwardly extending tubular member 22 has its lower end flattened and connected with the ring opposite the opening in the ring, as shown in Figure 7 and an angle bar 23 is adapted to be placed in the upper

end of this tubular member and to be held in adjusted position therein by a bolt 24 passing through a hole in the tubular member and any one of a plurality of holes 25 in the bar 23. The parts are so arranged that the upper limb 23' of the bar will remain in upright position no matter which hole 25 the bolt 24 is placed in. The upper end of the bar 22' is pointed as shown in Figure 9 and this part 22' is adapted to be passed through the holes in the parts 17 and 16 and the holes in the brackets and plate 9 and to rest against the upper limb of the part 16 so that the cowl is rotatably supported by this member 23 and the member 22. By having the member 23 adjustable in the member 22 the member 23 can be adjusted so that it will be centered in respect to the stack S as the ring 20 is adjusted to fit the stack.

As shown in Figure 1 the opening 4 in the bottom of the cowl is larger than the external diameter of the stack so as to leave a narrow space between them.

A vertically arranged vane 26 is fastened to the center of the top of the cowl to keep the cowl in the wind or in a position where the wind will enter the opening 8 and pass between the plate 9 and the top of the cowl and then will pass out through the large end of the cowl so as to create a suction or draft in the stack to facilitate the passage of smoke and gases therefrom and also to increase the draft of the stove or furnace connected with the stack.

I also provide a deflector 27 at the outlet end of the cowl which is connected by the bars 28 with the lower part of the outlet end of the cowl and a plate-like member 29 connects the top part of the deflector 27 with the vane 26 by having a U-shaped part 30 fitting over the front edge of the vane and connected thereto by rivets 31 or the like. This deflector is formed of a substantially semi-circular blank shown at 27' in Figure 10 with a portion of its rim bent outwardly and upwardly as shown at 32 and the internal part of the blank is of arcuate shape and flares outwardly and downwardly as shown at 33.

From the foregoing it will be seen that when the device is supported at the top of the stack or chimney by the ring 20 and the members 22 and 23 the cowl with the parts attached thereto can rotate and the vane 26 will keep the cowl in a position so that the wind will enter the opening 8 and pass through the passage formed by the plate 9 and the top of the cowl and then through the large end of the cowl, the wind being forced upwardly and outwardly by the lip 11 of the plate 9. As before stated this will cause suction to take place in the chimney or stack.

If for any reason there should be a gust of wind directed toward the large end of the device which ordinarily would enter the device and pass down the chimney to interfere with the draft and possibly blow smoke and gases from the stove into the building, such wind is prevented from entering the device by the deflector 27 as some of the wind striking this member would be deflected downwardly and outwardly away from the cowl and some of it might be directed upwardly and outwardly and sidewise by the part 32. In any event very little if any of the wind would enter the device.

This is useful where the cowl is placed on a stack or chimney located adjacent a tall building for in this case there is a possibility of a high wind striking the building and then being deflected thereby into the device. This deflector

is also advantageous in case the cowl should become stuck on the supporting means and fails to rotate for in this case if the cowl remains in a position where the wind might tend to blow into the large end thereof this deflector 27 would tend to prevent the wind so doing.

It is thought from the foregoing description that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A cowl device of the class described comprising a supporting member adapted to be connected to a stack or chimney top, a cowl body rotatably supported from said member and including a large outlet opening at one end and a small inlet opening at the other end, a plate spaced from the top of the cowl and forming a passage between itself and said top which is in communication with the inlet opening, a vane at the top of the cowl for holding the device in a position with the small inlet opening facing the wind and a deflector member at the outlet end of the cowl for preventing air flowing into said outlet opening, means for supporting the deflector member in spaced relation from said end of the body which has the outlet opening therein and said deflector member having its major portion sloping downwardly and away from the body and a flange portion sloping outwardly and upwardly from the top and sides of the major portion.

2. A cowl device of the class described comprising a body having a large opening in its bottom, straight sides and an arcuate top which slopes from one end to the other end, an end piece at said other end spaced from the top to form an inlet opening, a plate spaced from the top and forming a passage between itself and said top, said space being in communication with the inlet opening, a bracket connected with the plate and with parts of the cowl body, a supporting member rotatably engaged by the bracket, a vane extending from the top of the cowl body for holding the cowl with the end having the inlet opening therein toward the wind, a deflector, bar members connected with the body for holding the deflector in spaced relation to the large end of the cowl body, said deflector being formed with flaring parts for deflecting the wind away from the outlet end of the body.

3. A cowl device of the class described comprising a body having a large opening in its bottom, straight sides and an arcuate top which slopes from one end to the other end, an end piece at said other end spaced from the top to form an inlet opening, a plate spaced from the top and forming a passage between itself and said top, said space being in communication with the inlet opening, a bracket connected with the plate and with parts of the cowl body, a supporting member rotatably engaged by the bracket, a vane extending from the top of the cowl body for holding the cowl with the end having the inlet opening therein toward the wind, a deflector, bar members connected with the body for holding the deflector in spaced relation to the large end of the cowl body, said deflector being formed with flaring parts for deflecting the wind away from the outlet end of the

body, said cowl body being formed of a single piece of material.

4. A cowl device for the upper end of a stack or chimney comprising a split ring expansible for fitting different sizes of chimneys or stacks, a tubular bracket extending upwardly and inwardly from a portion of the ring, a rod bent to provide a straight upper portion vertically arranged and a sloping lower portion, said sloping lower portion having a sliding fit in the tubular member, means for holding said lower portion in adjusted position in the tubular part, and a cowl body rotatably supported by the straight vertical part of the bar.

5. A cowl device for the upper end of a stack or chimney comprising a split ring expansible for fitting different sizes of chimneys or stacks, a tubular bracket extending upwardly and inwardly from a portion of the ring, a rod bent to provide a straight upper portion vertically ar-

20 ranged and a sloping lower portion, said sloping lower portion having a sliding fit in the tubular member, means for holding said lower portion in adjusted position in the tubular part, and a cowl body rotatably supported by the straight vertical part of the bar, said body having an opening in its bottom fitting over the upper end of the stack or chimney with straight sides and an arcuate top which slopes from one end to the other, a wall forming part closing said other end of the cowl body and said wall forming part having a small opening at its top, the other end of the cowl body being open, a plate in the cowl body spaced from the top and forming a passage between itself and the top for the passage of air entering the small opening and a bracket in the cowl body having holes therein for fitting over the vertical part of the bar and a bearing part engaging the top of the bar.

DANIEL FRIEDMAN.
